Primary Examiner—Celia Murphy**CLAIM**

The ornamental design for a package for a multiple of contact lenses, as shown and described.

DESCRIPTION

FIG. 1 is a perspective view of a package for a multiple of contact lenses showing our new design;

FIG. 2 is a left side elevational view thereof; the right side being a mirror image thereof;

FIG. 3 is a top plan view thereof;

FIG. 4 is a front elevational view thereof;

FIG. 5 is a rear elevational view thereof; and,

FIG. 6 is a bottom plan view thereof.

The broken lines shown throughout the views are understood to represent perforations.
